UNITED STATES PATENT OFFICE

105,130

DESIGN FOR A DUST BAG FOR VACUUM CLEANERS

John R. Morgan, Oak Park, Ill., assignor to Sears, Roebuck and Co., Chicago, Ill., a corporation of New York

Application April 29, 1937, Serial No. 69,067

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Dust Bag for Vacuum Cleaners, of which the following is a specification, reference being had to the accompanying drawing, forming a part thereof.

Figure 1 is a plan view of a dust bag for vacuum cleaners embodying my new design, and Figure 2 is a sectional view taken on line 2—2 of Figure 1.

I claim:

The ornamental design for a dust bag for vacuum cleaners, as shown.

JOHN R. MORGAN.
